UNITED STATES PATENT OFFICE.

WILLIAM SAKLAD, OF BOSTON, MASSACHUSETTS.

LAST.

Application filed August 26, 1925. Serial No. 52,582.

My present invention relates to lasts, and more particularly to an improved last used in the manufacture of boots and shoes designed to support the arch of the foot of the wearer.

A properly designed boot or shoe to support the arch of the foot of the wearer or to retain the shape of the arch of the foot should provide proper support for both the transverse and longitudinal arch. Such a boot or shoe is clearly described and claimed in my copending application Serial No. 61,952 filed Oct. 12, 1925. My present invention relates to an improved last over which such boots or shoes may be built, and in carrying out my invention I so construct the inside ball of the bottom of the last as to fit the sesamoid bone and the first metatarsal phalangeal joint. Further the inside ball is constructed to fit the fifth metatarsal phalangeal joint, thus forming an arch between the first and fifth metatarsal phalangeal joints, to thereby support the anterior transverse arch. The contour of the bottom of the last, extending from the ball to the toe, is constructed to give freedom to the movement of the toes of the wearer of the shoe built on the last. I also provide an extension on the forepart of the last to allow for an elongation of the longitudinal arch, to thereby provide freedom of action of the toes. I find that by taking in on the waist line of the last and leaving a fullness of the ball measure, that a boot or shoe built on the last will hug the waist part of the foot, as well as the inner and outer longitudinal arches, thus preventing forward slipping of the foot of the wearer. I also provide sufficient cone or instep measure for the dorsum, or top, of the foot, thereby preventing shutting off of the blood supply. Further, the outside drop shank and cuboid extension are so constructed as to support and give comfort to the outer longitudinal arch of the foot, while the inner longitudinal arch section gives full support to the metatarsal, cuneiform and the scaphoid bones, thus permitting flexibility, giving comfort to the foot and supporting the inner longitudinal arch. Again, the curve of the heel seat permits the os calcis or heel of the foot to rest in the natural position, the back line or heel curve is so constructed as to conform to the natural line of the foot, while the sides of the last ensure close ankle fit of the boot or shoe built thereon.

The principal object of my invention therefore, is an improved last for orthopedic boot or shoes.

Another object is an improved last for the manufacture of boots or shoes having built-in arch supporting devices.

Other objects and novel features of construction will appear as the description of the invention progresses.

In the accompanying drawings illustrating a preferred embodiment of my invention,

Fig. 1 is a side elevation, partly in section, 70

Fig. 2 is a bottom plan view,

Fig. 3 is a sectional elevation, taken on the line 3—3 of Fig. 1,

Fig. 4 is a sectional elevation, taken on the line 4—4 of Fig. 1, and

Fig. 5 is a sectional elevation taken on the line 5—5 of Fig. 1.

Referring to the drawings, 10 designates a last of the block type, although it is obvious that any other type of last, such as a two part last, may be employed. This last represents, in general outline, the human foot, 11 being the toe portion, 12 the cone and 13 the heel. On the bottom of the last the longitudinal arch extends from the point 14 on the ball to the point 15 adjacent to the rear end of the heel 13. The ball of the bottom of the last is cut away as indicated in Figs. 1, 2 and 3, to form a depression 16 and the inside portion thereof fits the sesamoid bone and the first metatarsal joint 18 of the foot, while the outside portion 17 thereof fits the fifth metatarsal joint. This construction provides a transverse arch of proper length and which supports the anterior arch of the foot. A boot or shoe built on such a last will prevent callouses and allow more spring to the step of the wearer. Further, when building a boot or shoe on this last, it is feasible to have the insole conform to the contour of the depression 16, thereby making it possible to construct a boot or shoe with an integral arch support.

The bottom of the heel 13 is convex, as clearly shown in Fig. 4, and the bottom of the heel and the bottom of the arch join on a well defined line 19, extending transversely of the last, this joining line being shown in Fig. 5, as markedly convex. The curve of the heel seat permits the heel of the foot to rest in a natural position, thus preventing the spurs often caused by poorly or incorrectly constructed heel seats, and the

back line or heel curve is constructed to conform with the natural line of the foot. drop shank and cuboid extension being so constructed as to result in the supporting 30

The depression 16 is located at such a point that the arch of the foot of the wearer

- 5 of the boot or shoe built thereon is supported at the ideal or proper position to correct falling or fallen arches and to maintain normal arches in their original condition, while yet allowing the supporting
- 10 muscles of the foot to properly and naturally flex, as they must do to maintain their strength.

Having thus described my invention, what I claim as new, is:

- 15 1. An improved last provided with a longitudinal instep arch extending from the ball of the toe portion to adjacent the rear end of the heel, a recess in the bottom of the last, separate from the longitudinal arch, to permit an arch supporter to be formed in the shoe made on said last between the first and fifth metatarsal joints to support 40 the anterior arch of the foot, the front wall of said recess extending substantially perpendicular to the plane of the bottom fore-part of the last, the bottom of the recess sloping gradually toward the rear of the 45 shank portion of the last, and the sides of said recess sloping sharply to the shank of the last, the longitudinal arch being elongated forwardly of said recess and extending rearwardly to adjacent the rear end of 50 the heel to permit natural positioning of the os calcis in the shoe made on said last.
- 20 2. An improved last provided with a longitudinal instep arch extending from the ball of the toe portion to adjacent the rear end of the heel, a recess in the bottom of the last, separate from the longitudinal arch, to permit an arch supporter to be formed in the shoe made on said last between the first and fifth metatarsal joints to support the anterior arch of the foot, the front wall of said recess extending substantially perpendicular to the plane of the bottom fore-part of the last, the bottom of the recess sloping gradually toward the rear of the shank portion of the last, and the sides of said recess sloping sharply to the shank of the last, the longitudinal arch being elongated forwardly of said recess and extending rearwardly to adjacent the rear end of the heel to permit natural positioning of the os calcis in the shoe made on said last.
- 25 3. An improved last provided with a longitudinal instep arch extending from the ball of the toe portion to adjacent the rear end of the heel, a recess in the bottom of the last, separate from the longitudinal arch, to permit an arch supporter to be formed in the shoe made on said last between the first and fifth metatarsal joints to support the anterior arch of the foot, the front wall of said recess extending substantially perpendicular to the plane of the bottom fore-part of the last, the bottom of the recess sloping gradually toward the rear of the shank portion of the last, and the sides of said recess sloping sharply to the shank of the last, the longitudinal arch being elongated forwardly of said recess and extending rearwardly to adjacent the rear end of the heel to permit natural positioning of the os calcis in the shoe made on said last.

In testimony whereof, I have signed my name to this specification.

WILLIAM SAKLAD.
